CLAIM

The ornamental design for a kitchen rack, as shown and described.

DESCRIPTION

FIG. 1 is a front perspective view of a kitchen rack, showing my new design;

FIG. 2 is a rear perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 1;

FIG. 11 is a partial enlarged view of FIG. 1;

FIG. 12 is a partial enlarged view of FIG. 2;

FIG. 13 is a partial enlarged view of FIG. 2; and,

FIG. 14 is a partial enlarged view of FIG. 2.

The broken lines in the figures are for the purposes of illustrating portions of the kitchen rack, which form no part of the claimed design. The dash-dot broken line shown in FIGS. 1, 2, 9–14 is included for the purpose of illustrating boundary of enlargement and forms no part of the claimed design.
